LITHOGRAPHIC PRESS WITH COMBINED
INKING AND WATER SPRAY DAMPENING

William W. Davidson, Jr., Evanston, Ill.

Application January 6, 1950, Serial No. 137,183

3 Claims. (Cl. 101—147)

1

In lithographic offset printing a rubber blanket transfers the printing to the copy sheets from an inked plate, the ink-bearing portions of which must be repeatedly re-inked without inking the clear portions. This is accomplished by keeping the clear portions damp. Thus the plate is rolled first by one or more dampening rolls and then by one or more inking rolls.

Lithographic printing is an old art and for many years has been simplified enough for use on office type presses. Nevertheless it still requires rather delicate adjustments with the result that unskilled operators have much trouble. If a little too much water or dampening solution is applied, the unskilled will notice that the prints are running light and will increase the supply of ink. In turn, this may cause an ink scum to start spreading over the plate, leading the unskilled operator to apply still more water, etc. Eventually this leads to various other troubles, one being that the excess ink works back into the water rollers and may permanently harm them.

Various attempts have been made to avoid this need for critical adjustment and to simplify the operation of the press. An emulsified mixture of ink and dampening fluid fed by one set of applicator rolls has been tried. It was a failure commercially because of the poor quality of the printing. A set of convergent branches, one for water and one for ink, with a common final applicator roll for the two branches, has simplified the structure but with a greater tendency for ink to work back through the water rolls.

According to the present invention, water is supplied directly or indirectly to the ink-applying form roll by spraying. In this way it is possible to spread the water uniformly along the form roll and to mix or coat the ink with it so that it does a perfect job of dampening the plate without any danger that the ink will work back into the water mechanism. The ink tends to refuse to accept much excess water, or any more than can be disposed of by evaporation. The ink can carry excess water back to other ink rolls where small excesses can evaporate harmlessly. Thus both the critical adjustment for the water supply and all danger of gumming up the water attachment with ink are avoided.

Water spray has been tried before but not with these advantages. When the spray is applied directly to the plate, an excess must be applied to ensure that every bit of the clear part of the plate is reached. The gumming up of the water attachment is avoided, while the need for critical adjustment remains.

2

Other advantages and objects of the invention will be apparent from the following description and the drawings.

General designation of figures

5 Figure 1 is a diagrammatic view representing a longitudinal cross section of one form of the invention chosen for illustration.

10 Figure 2 is a diagrammatic view representing the face view of the water-applying device of Figure 1.

Figure 3 is a fragmentary diagrammatic view showing a modified form of the invention.

15 Figure 4 is a fragmentary diagrammatic face view of the structure seen in Figure 3 as viewed from the left.

General description

20 Although the invention is useful with any lithographic type of machine, it has been illustrated as used with a two-cylinder type of press commonly used as an office duplicator. Thus in the illustrated form, the press includes a large cylinder 11 and a small cylinder 12. The large cylinder 11 has a plate holding segment 13 to which a plate 14 bearing the matter to be printed is attached. After the plate 14 is properly inked, it rolls against a rubber blanket carried by cylinder 12 frequently called the "blanket roll." A 25 reverse ink impression of the matter being printed is thus applied to the blanket roll. Thereafter a sheet of paper to be printed is fed by the feeder 16 to pass between the cylinders in registration with the impression on the blanket so that the 30 ink of this impression will be printed on the sheet at the desired position thereon. As the sheet passes through the bite between the cylinders it is backed up by a platen segment 17. The 35 printed sheet is discharged to a catch box or discharge device 18. As a matter of practice, it may be turned over first by means not shown, so that it will be deposited on a pile printed side up.

35 The ink is applied to plate 14 by a series of inking rolls, the first of which, 21, is sometimes called the "fountain roll" and picks up ink from a supply held against it by an adjustable blade 22. The 40 roll or rolls at the end of the series of inking rolls and which bear against the plate 14 are called "form rolls." In the illustrated form of the invention, there are two form rolls, 23 and 24. The 45 present invention relates to this inking assembly or attachment.

50 Although the law requires a full and exact description of at least one form of the invention, such as that which follows, it is, of course, the

purpose of a patent to cover each new inventive concept therein no matter how it may later be disguised by variations in form or additions of further improvements, and the appended claims are intended to accomplish this purpose by particularly pointing out the parts, improvements or combinations in which the inventive concepts are found.

Need for dampening

In lithographic printing, it is necessary to dampen the plate 14 and to maintain the ink-free portions of the plate thereof in a damp condition so that ink from the form rolls 23 and 24 will not stick to these ink-free portions. Thus the dampening of the plate gives it a selective affinity for the ink. Although the ink from the form rolls 23 and 24 will not adhere to the damp ink-free portions of the plate, it will adhere to and therefore will ink the image or printing portions of the plate.

Description of novel feature

According to the Figure 1 form of the present invention, the dampening is accomplished by spraying water (dampening solution) onto the first form roll 23. This has been shown diagrammatically as accomplished by a spray tube 26 which extends along the length of form roll 23. The spray tube 26 should project a finely divided spray of water uniformly along the length of the ink-applying portion of form roll 23. To make the drawings more fully illustrative, this is represented diagrammatically in Figure 2. Thus the tube 26 is slotted on the side thereof facing roll 23 and a water spray is blown into each end of the tube by an air nozzle 27 which blows a jet of air across a water nipple 28. The jet of air draws water from the nipple 28 and atomizes it so that it can easily carry the water into the tube 26 and out through the slot 29 thereof against the entire length of the inking portion of form roll 23. The tube 26 may be longer, so that nipples 28 lie within it, if desired.

The normal water level is maintained at a constant depth close enough to the tip of nipples 28 so that the water will be drawn therefrom by the air jet. This may be accomplished by a conventional dampening fountain construction in which a container 31 of dampening solution is inverted into a pan 32 from which the solution runs through pipes 33 to the nipples 28. It may be noted that the conventional dampening solutions are mainly water and the terms "water" and "dampening solution" are used interchangeably.

Although the application of the spray to any point of the inking rolls is within the contemplation of this invention, it is at present preferred that the point of application be separated by at least one bite between inking rolls from the bite of the form roll with the plate. Thus in Figure 1 the water from the spray tube 26, after being applied to the roll 23, passes through the bite between roll 23 and distributor roll 36 before it reaches the plate 14. In other words, although the spray tube 26 appears to be adjacent the plate 14, it is separated from it operationally by the bite between form roll 23 and distributor roll 36. The separation by such a bite is generally preferred because it spreads the dampening fluid out more uniformly.

After the inker assembly has been driven enough so that the various rolls thereof are coated with ink, the spray will be started. If it is found to take some time before enough water from the spray has worked into the ink for successful

printing, the form rolls 23 and 24 will, until then, be raised from the plate 14. According to a modified form of the invention, the tube 26 may be positioned, or may be shiftable to be positioned, at the upper or left hand side of form roll 23 so as not to be separated from the plate by a bite between ink rolls. This may be desired for situations in which adequate dampening would otherwise not be dependably obtained.

10 Applying the dampening spray to the ink rolls at any point thereof instead of directly to the plate is a feature of this invention. It is believed that applying the spray directly to the plate would be very likely to result in either inadequate dampening of some spots of the plate or excessive dampening of others, or at least in a tendency toward such unequal distribution which would make adjustment for satisfactory printing very difficult, especially for inexperienced operators.

15 20 A drip trough 31 is preferably provided below spray tube 26 to catch any water which drips from it and to conduct it to a drain tube 38.

To ensure evaporation of excess dampening fluid which may work back to ink rolls 39 or to 25 second form roll 24, a blast of air (heated if desired) may be directed on them by a nozzle 40, or a plurality of such nozzles.

Modification

30 Another form of the invention has been shown in Figures 3 and 4. In this form the inker roll to which the spray is applied is not one of the main train of rolls, but is an extra distributor roll 41. This roll 41 has been shown running in contact with the form roll 23 on the side of the 35 latter approaching the plate 14. By rearranging parts it could engage the form roll 23 elsewhere or it could engage one of the other inker rolls. The illustrated position is preferred because it will result in relatively little dampening solution working its way from form roll 23 to distributor roll 36.

The illustrated arrangement of roll 41 and the roll with which it engages has another advantage. Spray tube 26 may be positioned below roll 41 so 45 that any excess water gathering on the surface of spray tube 26 will run away from the slot 29 therein thus reducing the chance that large drops of water will cause any difficulty. This danger is further reduced by virtue of the fact that if an 50 excess of water is applied to the roll 41 it will be carried around the roll and collected in trough 42 between the roll 41 and form roll 23. Should the spray tube 26 continue to apply an excess of water to roll 41, the excess will accumulate in 55 trough 42 until it runs to the ends of the rolls and drips into drip pan 43. It will be observed that the inker rolls such as 23 and 41 are commonly wider than the press roll 11 so that it would be 60 easy to catch the drippings from the ends of such rolls even if they were not positioned to the side of roll 11 as seen in Figure 3. An air nozzle 45 may be provided for blowing water from this trough as fast as it accumulates. This feature may be used in other forms of the invention 65 wherever water tends to accumulate.

The second form roll 24 is relatively free from water and hence ensures perfect inking for high quality printing. It may be understood that according to conventional practice the amount of 70 ink fed may be regulated by adjusting blade 22 (Figure 1) and by varying the proportion of time that ductor roll 46 engages ink fountain roll 21. All of the rolls rotate constantly except fountain roll 21, which is intermittent and preferably adjustable, and ductor roll 46, which is free.

From the foregoing it is seen that a lithographic press has been devised in which the correct supply of dampening solution to the plate is easily accomplished without any danger of gumming up the dampening mechanism so as to impair its function for supplying the dampening solution. By applying water spray to an inking roller, the danger of excessive application of water to the plate is virtually eliminated.

According to another aspect of the invention, water is applied to the inking assembly and is largely confined to the desired path of feed and to satisfactory concentrations by applying drying influences to ink rollers on which the water is not desired.

The amount of excess water which needs to be evaporated (with any type of water supply feeding an excess) can be reduced by blowing away any water that accumulates as droplets in troughs formed by the rolls. This will often enable the excess to evaporate naturally. At present it is preferred to avoid directing such an air blast along the the plate roll where it might objectionably dry the plate.

I claim:

1. A lithographic press including a plate holder, an ink-applying unit including a final ink form roll and supply and distribution means including at least one preliminary roll engaging said form roll, an inker branch including an ink form roll engaged by the plate as it approaches the final form roll and supplied with ink from said supply and distribution means, a sprayer for applying a spray of aqueous ink repellent to the inker branch whereby repellent is received by the form roll thereof predominantly over the final form roll,

and drying means adjacent to the unit other than to said branch and along the course of ink movement therein beyond said branch whereby the final form roll is maintained relatively free of repellent.

2. A lithographic press in accordance with claim 1, in which the sprayer is positioned for applying the ink repellent to a surface approaching the line of contact between the ink form roll 10 of the branch and an ink distribution roll engaging said form roll.

3. A lithographic press in accordance with claim 1, in which the sprayer is positioned to apply the spray to the ink form roll of the branch at 15 a portion thereof which is leaving the plate holder and is approaching a line of contact with a distribution roller along which ink moves in said branch toward said ink form roller thereof.
